CLOTHES HAMPER

Carl Fuerst, New York, N. Y., assignor to Gleitsman's, Inc., Long Island City, N. Y., a corporation of New York

Application May 23, 1951, Serial No. 227,783

4 Claims. (Cl. 312—211)

1 This invention relates generally to clothes hampers.

One object of the present invention is the provision of a clothes hamper having a main receptacle for soiled clothes and linen and a compartment which may be used to contain articles of a different character segregated from the contents of the main compartment.

Another object of the present invention is the provision of a clothes hamper which has integrated therewith a separate article compartment which is normally concealed from view, for example, when the back of the hamper is disposed adjacent to the wall of a room.

Another object of the present invention is the provision of a clothes hamper which has integrated therewith a separate article compartment, the hamper resembling a conventional hamper in all respects in the normal positioning of the hamper in a room.

Another object of the present invention is the provision of a clothes hamper having a separate article compartment which is of improved construction and appearance and in which articles, especially a brush for cleaning the bowl of a water closet, may be disposed and concealed from view.

Yet another object of the present invention is the provision of a clothes hamper having a separate article compartment which takes up no more space than a conventional clothes hamper.

Other objects, features and advantages of the invention will become apparent as the description thereof proceeds when considered in connection with the accompanying illustrative drawings in which:

Fig. 1 is a front perspective view of a clothes hamper embodying the present invention, the cover being shown in open position;

Fig. 2 is a side elevational view of the clothes hamper, parts being shown cut away, for illustrative purposes;

Fig. 3 is a rear view of the hamper;

Fig. 4 is a sectional view taken on the line 4—4 of Fig. 3; and

Fig. 5 is a sectional view similar to Fig. 4, showing a modification.

Referring to the drawings in detail, and more particularly to Figs. 1 to 3 thereof, there is shown a hamper 10 which comprises a closed bottom 12, upright wall 14, a top cover 16, a rear wall 18, and a separate article compartment 20. Said rear wall 18 may be made from wood or sheet metal or any other suitable material. Wall 14 may be made from any conventional material, such as wicker work, as indicated at W. The

2 top 16 of the hamper 10 is hinged to said hamper at 22 and is swingable from the normally closed position shown in Figs. 2 and 3 to an open position shown in Fig. 1 for access to the main compartment which normally serves as a storage receptacle for soiled clothes and linen. As shown in Fig. 4, the bottom 12 of the hamper 10 is suitably perforated as at 26, providing air holes for main compartment 24 of the hamper.

In the presently preferred embodiment of the invention, the separate article compartment 20 is constituted in part by a forwardly recessed portion 28 of the rear wall 18, as shown in Figs. 1, 2 and 4. Said recessed portion 28 is of generally semi-circular cross-section, but it will be understood it may be any other suitable contour. The back of the compartment 20 may be left open and lies in the plane of the rear wall 18. As shown, the recessed wall portion 28 of the rear wall 18 extends vertically of the hamper for the full height of said rear wall and is positioned substantially centrally thereof. It will be readily apparent that the recessed wall portion 28 of the rear wall 18 forms the upright side walls of the article compartment 20.

With reference to Fig. 3, the separate article compartment 20 is provided with a top wall 30, which is preferably formed of sheet metal which is secured at the top of wall portion 28 internally of the latter. Said compartment also includes a bottom member 32, and a plurality of horizontally disposed shelves 34, located intermediate the top wall 30 and the bottom member 32 which rests on the bottom 12 of the hamper. For ease of construction and assembly, the top wall 30, the bottom member 32 and the shelves 34 may be identically dimensioned and constructed so that all of said parts may be mass produced. If desired, the bottom member 32 may be removable so that said member may be used as a drip pan, as will be readily understood. Top 30, member 32, and shelves 34 are all provided with peripherally extending flanges 36 so that said parts may be readily secured to the recessed wall portion 28 of the rear wall 18 by any conventional means, such as welding, riveting, and the like. When member 32 of the compartment 20 is removably secured in said compartment to be used as a drip pan, the flanges 36 of said wall 32 will be disposed in upstanding disposition so as to contain the drippings. The top wall 30 of the compartment 20 has suitably secured thereto support provisions such as hooks 38 for the support of a wide variety of household articles in the compartment 20, for example a brush B. The shelves 34 of the compartment 20 are provided with vertically

50 55 56

aligned cutout portions 40 (Fig. 3) which are provided for the reception of brush handles or other elongated articles. It will therefore be seen that the compartment 20 is readily adapted to contain a plurality of articles separate from the main compartment 24 of the hamper, and said compartment 20 may readily contain an elongated article, such as a bathroom brush B, in a very efficient and compact manner by hanging brush B on the hook 38 with the brush handle depending from said hook in the vertical aligned cut-out portions 40 of the shelves 34.

With reference to Fig. 5, there is shown a view of a hamper embodying the above described concept in a modified form. In the modification shown in Fig. 5, the article compartment 20 is formed as a separate unitary structure 41. For this purpose, the upright side walls 14' of the hamper 10 include rear wall portions 42, only one of such wall portions being shown in Fig. 5, which are spaced apart for the reception therebetween of the separate unitary article compartment or structure 41. The spaced rear wall portions 42 of the side walls 14' form a continuation of said side walls and may be fabricated from the same material as said side walls. Thus, in the modification shown in Fig. 5, there is no rear wall panel 18 as in Figs. 1 through 4, instead the side walls 14' are provided with spaced rear wall portions 42 which are a continuation of said side walls, and the article compartment 41 is positioned between and suitably affixed to said rear wall portions 42. As clearly shown in Fig. 5, the ends of the rear wall portions 42 may be clamped in a longitudinal U-shaped clamp 44 it being understood that said clamp 44 extends for the full length of said rear wall portions 42.

The article compartment 41 comprises upright side walls 28', a top wall 30, bottom wall 32 and shelves 34, as described in reference to Figs. 1 through 4, said compartment 41 however being formed as a separate unitary compartment. The ends of the upright side walls 28' are provided with outwardly extending flanges 46 which are secured to the outside face of the clamp 44 in any conventional manner. In this modified form, there is provided an angle iron bracing member 48 which is suitably affixed to the inside rear corners of the side walls 14', as by rivets 49, to impart further rigidity to the structure. It will thus be seen that the modified form of construction of hamper 10 provides for the article compartment being formed as a separate unitary structure whereby hamper 10, having a separate article compartment 20, may have its manufacture and assembly facilitated.

It will be readily apparent that the hamper 10, having the separate compartment 20, is readily adapted for a multitude of household uses, and the compartment 20 may be used to contain a wide variety of household articles. The separate article compartment 20 is completely concealed from view when the hamper is disposed adjacent to the wall of a room. In the normal positioning of the hamper in a room, it resembles a conventional hamper in all respects and takes up no more space than a conventional hamper. It is also readily apparent that the hamper 10, which is of improved construction and appearance, may be used to contain elongated articles such as bathroom brushes, which may be stored and concealed from view in the supplemental compartment 20.

A hamper of the present invention may be used to advantage in the bathroom and positioned so

that the opening of compartment 20 at the back of the hamper is closed by the bathroom wall adjacent to which the hamper is placed. When thus used in a bathroom, said compartment 20 provides a very convenient place to contain and conceal a water closet brush. It will be observed that compartment 20 is not provided with a cover for the access opening thereof provided at the back of the hamper, this being unnecessary even when said compartment is used to contain various small articles not held in place, since the wall against which the hamper is placed will act as a cover for said opening. However, it will be understood that it is within the scope of this invention to provide a cover for said compartment opening. Also, it will be understood that if desired the top 30 may be movable or removable to provide access to the compartment 20 through the top opening of the hamper when cover 16 is opened.

While there is shown and described herein certain specific structure embodying the invention, it will be manifest to those skilled in the art that various modifications and rearrangements of the parts may be made without departing from the spirit and scope of the underlying inventive concept and that the same is not limited to the particular form herein shown and described except insofar as indicated by the scope of the appended claims.

Having thus described my invention, what I claim and desire to secure by Letters Patent, is:

1. A hamper, comprising an open receptacle having a top, a bottom, and vertical walls including a rear wall, said rear wall having a portion thereof recessed towards the front of the hamper and extending substantially vertically thereof, said recessed portion being open at the back of the hamper and having a closed top and bottom and at least one horizontally positioned shelf disposed intermediate said top and bottom of said recessed portion, the latter forming a concealed compartment separated from said receptacle for the storage of articles when said rear wall of said hamper is disposed adjacent to the wall of a room, and a top cover movable between open and closed positions, the latter position being effective to cover said receptacle and said closed top of said concealed compartment.

2. A hamper having a main compartment comprising a top, a bottom, and upright walls including a rear wall, said rear wall having a portion thereof recessed towards the front of the hamper, said recessed portion extending longitudinally of the hamper for substantially the length of said rear wall centrally thereof, said recessed portion forming a compartment separate from said main compartment and having a closed top and bottom and a plurality of horizontally positioned shelves disposed therein, said shelves having vertically aligned cut-out portions adapted for the reception of elongated articles and said closed top having means for supporting the elongated articles received in said cut-out portions.

3. A hamper having a main compartment comprising an open top, a closed bottom, and upright walls including a rear wall, said rear wall having an integral portion thereof recessed towards the front of the hamper and extending vertically of the hamper for the full height of said rear wall substantially centrally thereof, said recessed portion forming a compartment separate from said main compartment and having a closed top and bottom, a plurality of horizontally positioned shelves secured to said recessed portion, said sepa-

rate compartment being adapted to contain a plurality of articles separated from the contents of said main compartment by said integral portion of said rear wall, and a top cover movable between open and closed positions, the latter position being effective to cover said main compartment and said closed top of said separate compartment.

4. A hamper having a main compartment comprising an open top, a closed bottom, and upright walls including a rear wall, said rear wall having an integral portion thereof recessed towards the front of the hamper and extending vertically of the hamper for the full height of said rear wall substantially centrally thereof, said recessed portion forming a compartment separate from said main compartment and having a closed top and bottom, a plurality of horizontally positioned shelves secured to said recessed portion, said separate compartment being adapted to contain a plurality of articles separated from the contents of said main compartment by said integral portion of said rear wall, and a top cover movable between open and closed positions, the latter position being effective to cover said main compartment.

10 15 20 25

ment and said closed top of said separate compartment, said shelves having vertically aligned cut-out portions adapted for the reception of elongated articles and said closed top having means for supporting the elongated articles received in said cut-out portions.
